CLAIM

The ornamental design for cabinet handle, as shown and described.

DESCRIPTION

FIG. 1 is a perspective view of a cabinet handle showing our new design;

FIG. 2 is a perspective view of a cabinet handle showing our new design, the only difference being the length;

FIG. 3 is a top view of the cabinet handle shown in FIG. 2.

FIG. 4 is a front view of the cabinet handle shown in FIG. 2.

FIG. 5 is a cross section of the cabinet handle shown in FIG. 2.

FIG. 6 is a top view of the cabinet handle shown in FIG. 1.

FIG. 7 is a front view of the cabinet handle shown in FIG. 1; and,

FIG. 8 is a cross section of the cabinet handle shown in FIG. 1.

Portions of FIGS. 1–8 that are shown as broken lines are for illustrative purpose only and form no part of the claimed design.
